[57] ABSTRACT

In a cannon system, a change in the elevation angle of the cannon tube is converted to angular displacement of the yoke trunnions of the forward tripod support of the cannon tube. This angular displacement is sensed by a fluidic sensor which transmits a corresponding signal to a fluidic amplifier whereby the signal is amplified and transmitted to a cylinder for actuation of a piston therein responsive to the signal. The cylinder, piston and a piston rod form one leg of the tripod and the linear displacement of the piston acts to change the elevation of the tube to where it returns to the pre-selected angle of elevation as sensed by the sensor.

AUTOMATIC ELEVATION RECOVERY SYSTEM FOR CANNONS

The invention described herein may be manufactured, used and licensed by or for the Government without the payment to us of any royalty thereon.

BACKGROUND OF THE INVENTION

This invention relates to cannons and pertains more particularly to a control device for automatically recovering the adjusted elevation of a cannon when displaced therefrom.

Oftentimes cannons, because of the exigencies of war, have to be mounted on unstable terrain which permits the cannon to be displaced sufficiently responsive to recoil forces to move the cannon off target. This is particularly true of infantry mortars which are packed to areas, often of rough terrain, and then quickly set up, sighted on the target and fired. In such instances, a number of projectiles have to be fired before the mortar base plate is sufficiently entrenched to withstand further recoil forces without appreciable displacement. Consequently, mortars have to be resighted after firing each of the initial rounds and, as the only hitherto known practical means of resighting a mortar is by manual means, the resighting takes considerable critical time to thereby reduce the firepower of the mortar. Means have been attempted herebefore to automatically realign mortars with a target but they have been placed on the base plate which is subjected to flying debris during fire and even of being buried where the supporting terrain is sandy. Thus, the automatic mechanisms become fouled and consequently inoperable.

SUMMARY OF THE INVENTION

It is one object of this invention to provide for cannons a control system which automatically reestablishes the elevation thereof whenever displaced during fire from an adjusted setting.

It is a further object of this invention to provide such a system which is fluid actuated.

It is a still further object of this invention to provide such an automatic control system which is simple in design, compact in size, rugged in construction and reliable in operation.

These objects are achieved by adapting for cannon use the invention which is disclosed in our copending patent application for "Fluid Actuated Control System," U.S. Pat. Ser. No. 242005; Filed: Apr. 7, 1972. In this adaptation a change in the elevational angle of the cannon is converted to angular displacement of the sleeve trunnions which are part of the tripod support of the front end of the cannon tube. This angular displacement is sensed by a fluidic sensor which transmits a signal responsive to the angular displacement to a fluidic amplifier whereby fluid of unbalanced pressure is transmitted to opposite ends of a cylinder for linear actuation of a piston therein. The cylinder, piston and connecting piston rod form one leg of the tripod and the linear displacement of the piston serves to change the elevation of the cannon tube until it returns to the adjusted elevation as sensed by the sensor.

BRIEF DESCRIPTION OF THE DRAWINGS

FIG. 1 is an elevational view of a mortar system shown sighted on a target and with the cylinder of the automatic recovery system partially broken away to show the piston and connected piston rod therein;

FIG. 2 is a view similar to FIG. 1 but shows the base plate driven rearwardly, thereby misaligning the tube axis relative to the sight line of elevation;

FIG. 3 is a view similar to FIGS. 1 and 2 but shows the elevation of the cannon tube recovered by the recovery system;

FIG. 4 is an enlarged fragmentary view of the mounting yoke of the tripod and the sleeve pivotally mounted thereto, with the yoke shown partially in cross-section to disclose the sensing device therein;

FIG. 5 is a section taken along line 5-5 of FIG. 4;

FIG. 6 is a schematic view of the fluidic amplifier; and

FIG. 7 is an isometric, exploded view of the sensing device exclusive of the yoke arm in which it is mounted and with the sleeve fragmentized to show the interior structure of the device.

DESCRIPTION OF A PREFERRED EMBODIMENT

Shown in the drawings is a mortar system 12 comprising a firing tube 14, a base plate 16 pivotally mounted to the rear end thereof and a tripod 18 which slidably supports the front end of the tube. Base plate 16 is provided with a plurality of spikes 20 which project downwardly from the under side thereof so as to be entrenched into the supporting terrain responsive to the recoil forces produced in tube 14 when a projectile is fired therefrom.

Tripod 18, as shown in FIGS. 1-3, comprises a cylinder 22 which slidably accommodates a piston 24 with a piston rod 26 attached thereto. Cylinder 22, with piston 24 and piston rod 26, form the leg of tripod 18 which is coincident with a vertical plane defined by the longitudinal axis of tube 14. The other two legs 28 of tripod 18 are attached to the upper end of cylinder 22 so as to spread oppositely and outwardly therefrom. A spiked plate 30 extends from the bottom end of cylinder 22 and similar spiked plates extend from the bottom ends of legs 28 to secure tripod 18 against displacement when the spikes are driven into the supporting terrain.

The outer end of piston rod 26 is terminated by a yoke 32 having a pair of spaced arms 34 which receive therebetween a sleeve 36 having a bore 37 that slidably receives tube 14, allowing both linear and angular displacement relative thereto. Sleeve 36 is mounted to arms 34 for pivotal rotation about a diametrical axis by means of a pair of trunnions which include an axle 38 threaded into the outer circumference of the sleeve and a shaft 40 threaded thereinto in diametrical alignment with the axle. Shaft 40 includes a bearing portion 42 and a rotor portion 44 which extends outwardly therefrom and which is part of a sensing device 45 to be described hereinafter. Rotor 44 is connected to bearing portion 42 by means of a screw 46 having a head 48 of larger diameter. Screw 46 is received by a hole 50 which is axially bored through rotor 44 and counterbored at 52 to a shoulder 54 and which is threadingly engaged with a threaded bore 56 in bearing portion 42. Thus, when screw 46 is loosened, rotor 44 is free to be rotated thereabouts relative to bearing portion 42 and, when the screw is tightened, the rotor is frictionally secured to the bearing portion against angular displacement. Manual rotation of rotor 44 is facilitated by a knurled gripping portion 55.

Axle 38 is received by a bushing 58 in one arm 34, as shown in FIG. 4. Shaft 40 extends through a stepped

hole 59 in the opposite one of the arms 34 which is counterbored at 60 from the outside thereof to a shoulder 62. A sleeve 63 of sensing device 45, having a bore 61, is installed in counterbore 60 by press fit and a bushing 64 is installed in the smaller diameter portion of hole 59 for bearing contact with bearing portion 42.

A pair of segmental slots 65 are symmetrically formed in sleeve 63 from the outside circumference thereof, as shown in FIG. 5. Slots 65 are closed by the circumferential surface of counterbore 60 to define a right chamber 66 and a left chamber 67. A bottomed hole 68 extends radially inwardly from the circumference of sleeve 63 equidistant from the bottom ends of right chamber 66 and left chamber 67 and such hole has registry with a passage 69 in the respective one of the arms 34. Such passage 69 has communication with a source of low pressure fluid flow, (not shown) at approximately 5-7 psi, by means of a conduit 70. Fluid communication between hole 68 and chambers 66 and 67 is provided by restrictive orifices 72 and 74, respectively, which are disposed 180° apart in sleeve 63 and which have their axes normal to and intersecting with the axis of such hole.

Provided in rotor 44 where encircled by sleeve 63 is a pair of similar segmental channels 76 which are oppositely disposed and which are angularly related to each other with bottom edges 78 thereof diametrically spaced. The upper ends of channels 76 are interrupted by a segmental cut 80 which extends along rotor 44 to the free end thereof, as shown in FIGS. 5 and 7. Channels 76 are partially closed by the circumferential surface of bore 61 to define a right passage 82 and a left passage 84. Both passages 82 and 84 have fluid communication with an opening 86 which is defined by segmental cut 80 and the circumferential surface of bore 61. Fluid communication between right passage 82 and right chamber 66 is provided by an aperture 88 and a similar aperture 90 provides communication between left passage 84 and left chamber 67. Apertures 88 and 90 are disposed 180° apart and in axial alignment so that both may be simultaneously bisected by the respective one of the edges 78 when rotor 44 is disposed at a pre-selected angular position, as shown in FIG. 5, and wherein an index line 91 on gripping portion 55 is in alignment with a calibration 93 on outer face 95 of sleeve 63.

Thus, when the low pressure fluid flow from conduit 70 is permitted to pass into hole 68 it passes therefrom equally through right orifice 72 into right chamber 66 and through left orifice 74 into left chamber 67. From chambers 66 and 67 the low pressure fluid passes as two signal flows through an outlet 92, leading from right chamber 66, and another outlet 94, leading from left chamber 67, and also through the respective apertures 88 and 90, as controlled by the angular position of rotor 44, to passages 82 and 84 and therefrom to the ambient atmosphere. Consequently, the pressure and volume of the signal flows passing through outlets 92 and 94 are controlled by the amount of the fluid flow vented through apertures 88 and 90 from chambers 66 and 67, respectively, to thereby generate and transmit to outlets 92 and 94 fluidic signals relative to the angular position of rotor 44. When rotor 44 is rotated to where edges 78 divide apertures 88 and 90 equally, as shown in FIG. 5, the pressure and volume of the signal flows passing through outlets 92 and 94 are the same. When rotor 44 is rotated to an angular position

whereby the opening between left aperture 90 and left passage 84 is decreased, and the opening between right aperture 88 and right passage 82 is increased, the amount of the signal flow passing through outlet 94 is proportionally greater than that passing through outlet 92 and thereby produces a signal, transmitted through such outlet, which indicates the angular position of the rotor respective to the pre-selected angular position. The degree of angular displacement of rotor 44 which will produce a proportional signal is determined by the size of apertures 88 and 90, i.e., the greater the size of these apertures, as measured on or along the circumference of bore 61, the greater is the angular displacement of the rotor which will produce a proportional signal. When, through greater angular displacement of rotor 44, one of the apertures 88 and 90 is closed and the other is fully open a maximum differential signal is produced and transmitted from sensing device 45 by means of the fluid pressure which passes through outlets 92 and 94.

Outlets 92 and 94 connect, respectively, with input ducts 96 and 98 of a fluidic amplifier 100 which is of conventional type and is fully explained in the inventors' hereinbefore referenced copending application. Input ducts 96 and 98 communicate at a 180° angle with a junction 102 to which a high pressure fluid flow at approximately 30 psi is conducted by conduit 104 from a source (not shown). Two branches, including a left passage 105 and a right passage 106, extend from junction 102 in a "Y" configuration so that the high pressure fluid flow may be directed into either passage with no loss in momentum. Proportional deviation of the high pressure fluid flow at junction 102 into passages 105 and 106 is controlled by the signal flows conducted to the junction by means of input ducts 96 and 98.

As shown in FIG. 1, piston 24 is of double acting type and cylinder 22 is closed at one end and a seal is made at the opposite end where piston rod 26 extends therefrom. Right passage 106 is connected by conduit 107 to the top end of cylinder 22 and left passage 105 is connected by conduit 108 to the bottom end of the cylinder so that piston 24 is displaceable therein according to the amplified signal transmitted by the controlled fluid flow to the cylinder.

OPERATION

When mortar system 12 is set up on a supporting terrain, as shown in FIG. 1, with the longitudinal axis of cylinder 22 being substantially coincident with the vertical plane defined by bore axis $x-x$ of tube 14, the tube is sighted on the target by sighting means (not shown) so that axis $x-x$ is coincident with the adjusted angle of elevation $y-y$. With tube 14 sighted on the target, screw 46 is loosened and rotor 44 is turned through gripping portion 55 until index line 91 is aligned, with calibration 93. Thus, sensing device 45 is in balance with rotor 44 and disposed at the pre-selected angular position. Screw 46 is then tightened so that rotor 44 is angularly displaceable together with sleeve 36.

When a projectile is fired from tube 14, the recoil force is transmitted to base plate 16 and, if the terrain is not fully stable and spikes 20 are not driven thereinto to fix the base plate to the terrain, the base plate is driven rearwardly and downwardly, as shown in FIG. 2. Because of this displacement of base plate 16, axis $x-x$

of tube 14 is displaced from the adjusted angle of elevation and tube 14 is slidably displaced in sleeve 36, as shown. This displacement changes the angle of axis $x-x$ and causes sleeve 36 to be rotated accordingly about axle 38 and shaft 40. As rotor 44 is frictionally engaged with bearing portion 42 by means of screw 46, the rotor is consequently displaced angularly therewith, as explained hereinbefore, whereby responsive signals are transmitted to fluidic amplifier 100. The signals received by fluidic amplifier 100 are amplified and directed to opposite sides of piston 24 proportional to the difference between the two signal flows transmitted to the fluidic amplifier. Consequently, piston rod 26 with sleeve 36 are actuated upwardly, and forwardly along tube 14, to return bore axis $x-x$ back to the adjusted angle of elevation $y-y$. When angular displacement of rotor 44 by rotation of sleeve 36 reaches the pre-selected angular position the adjusted angle of elevation $y-y$ of tube 14 is recovered and mortar system 12 is back on target as to elevation. If the displacement of base plate 16 rotates rotor 44 to where the angular displacement thereof is beyond the limits wherein the signals from sensing device 45 are proportional, a maximum differential signal is produced until the rotor is returned within the limits wherein the proportional signals are effected, thereby expediting the return of mortar system 12 into alignment with the target.

We wish it to be understood that we do not desire to be limited to the exact details of the construction shown and described for obvious modifications will occur to a person skilled in the art.

We claim:

1. A cannon system comprising a projectile discharging tube disposed for angular displacement to an adjusted angle of elevation for sighting at a target, fluid actuated means for automatically recovering the adjusted angle of elevation of said tube responsive to displacement therefrom, said fluid actuated means including a sensing device responsive to angular displacement of said tube from the adjusted angle of elevation and means for generating a low pressure fluid signal according to the angular displacement, a fluidic amplifier for amplifying the low pressure signal to a fluid flow of greater pressure, and means responsive to the amplified fluid flow for returning said tube to the adjusted angle of elevation.

2. The invention as defined in claim 1 and including means for supporting the rear end of said tube, and means for supporting the front end of said tube, and wherein said means responsive to the amplified fluid flow comprises means for displacing one of said supporting means responsive to displacement of said tube from the adjusted angle of elevation for recovery thereto.

3. The invention as defined in claim 2 wherein said means for supporting the front end of said tube comprises a tripod including three spaced legs, and said means responsive to the amplified signal comprises a cylinder with a cooperating piston and a piston rod, and wherein said cylinder, piston and piston rod form one leg of said tripod.

4. The invention as defined in claim 3 wherein said means responsive to the amplified signal comprises a yoke mounted to said piston rod, and a sleeve pivotally mounted to said yoke, said sleeve having a bore adapted to slidably receive said tube for angular and longitudinal displacement relative thereto.

5. The invention as defined in claim 4 wherein said yoke includes a pair of spaced arms, said sleeve includes a pair of trunnions for pivotally mounting said sleeve to said arms, and wherein one of said trunnions includes at least one element of said sensing device.

6. The invention as defined in claim 5 wherein said one element of said sensing device includes a rotor, and wherein said sensing device also comprises a sleeve mounted in one of said arms for receiving said rotor, and said rotor and said sleeve include cooperating means for sensing the angular displacement of said sleeve from a selected angular position and generating a fluidic signal reflecting the degree of the angular displacement.

7. The invention as defined in claim 6 and including means for adjustably mounting said rotor for angular displacement relative to said sleeve to thereby adjust the selected angular position of said rotor 50 as to coincide with the adjusted angle of elevation of said tube.

8. The invention as defined in claim 7 and including means indicating coincidence of the selected angular position of said rotor and the adjusted angle of elevation of said tube.
